US00D493436S1

(12) **United States Design Patent** (10) Patent No.: **US D493,436 S**
Okada et al. (45) Date of Patent: **** Jul. 27, 2004**

(54) **MOBILE PHONE**

(75) Inventors: **Norio Okada**, Yokohamashi (JP); **Mihoko Hotta**, Kawasaki (JP)

(73) Assignee: **Matsushita Electric Industrial Co., Ltd.**, Osaka (JP)

(**) Term: **14 Years**

(21) Appl. No.: **29/174,605**

(22) Filed: **Jan. 21, 2003**

(51) LOC (7) Cl. **14-03**

(52) U.S. Cl. **D14/138**

(58) Field of Search **D14/137, 138, D14/218, 147-148, 247-248, 144, 341-347; 379/433.01-433.13, 419, 434, 428.01-428.04, 420.01-420.04, 440; 455/550.1-90.3; D21/517**

(56) **References Cited**

(57) **CLAIM**

The ornamental design for a mobile phone, as shown and described.

DESCRIPTION

FIG. 1 is a top perspective view of a mobile phone of the present invention;

FIG. 2 is a front view thereof;

FIG. 3 is a first side view thereof;

FIG. 4 is a top view thereof;

FIG. 5 is a second side view thereof;

FIG. 6 is a rear view thereof; and,

FIG. 7 is a bottom view thereof.
